UNITED STATES PATENT OFFICE

ROY E. HALLINGS, OF NEW YORK, N. Y.

ILLUMINATED TRANSPARENCY

Application filed June 18, 1928. Serial No. 286,173.

The present invention has relation to an improved ornamental illuminated "transparency" particularly useful for advertising signs, lamp shades etc., as well as to a process 5 for making the same.

The principal object of this invention is to supply a form of illuminated "transparency" which shall be substantially non-inflammable and by means of which a uniformly diffused, 10 and yet brilliant and sparkling, light, colored or otherwise, may be transmitted through suitable apertures or through a suitably ornamented surface, for advertising or other purposes. In the following description and 15 claims, the word "transparent" is intended to cover any suitable degree of capacity to allow the passage of light.

The principal object of the present invention is the production of an illuminated sign 20 so made as to combine the qualities of sparkling brilliancy with such a degree of light diffusion as will make all parts of the sign clearly and uniformly visible and agreeable to the eye.

25 Broadly stated, my invention comprises a "transparent" sheet, colored or otherwise, to which globules of transparent material, such as glass, are made to adhere, either on one or both sides, whereby a pleasant diffusion of transmitted light is accomplished, while preserving a brilliant effect. As adapted to illuminated signs in particular, a sheet or 30 sheets of this kind may be applied to an opaque sheet suitably cut out or otherwise 35 perforated and my invention will be herein described in this connection, although not necessarily confined to this use.

The invention is illustrated in a preferred 40 form, as applied to a "transparent" or illuminated sign, in the accompanying drawings, wherein Fig. 1 is a perspective view of a simple form of illuminated sign furnished with my invention, Fig. 2 is a horizontal sectional view of the same, and Figs. 3, 4 and 5 are 45 sectional views of a portion of the front plate of said sign in successive stages of manufacture.

In the form of illuminated sign shown in the drawings a suitable box or container 10 50 is furnished with one or more lamps 11 suit-

ably supported. These are preferably electric lamps. The front of the box is open and is furnished with a suitable frame 12 for carrying the sign proper indicated in Fig. 1.

This sign proper is preferably composed of a sheet of metal 13 which is punched or cut out in any manner desired, as for instance with the letters Sign as shown in Fig. 1.

The front of this sheet 13 may be painted, lacquered, electroplated or otherwise finished as shown at 14 and when the same is thoroughly dry the next step in the process of manufacture is to paint or spray the inner surface or back of this plate with transparent lacquer or similar quick drying adhesive 15, and while it is still wet I preferably apply a sheet of silk or like translucent fabric 16 which absorbs the adhesive on the back of the plate 13, and when dry, adheres firmly to the plate. The fabric may be dyed or otherwise 65 treated to produce a design or color effect.

When the fabric has dried sufficiently to make it adhere to the plate 13, the inner side or back of the same is painted or sprayed with lacquer 17 which may be clear or colored; 70 and this should be of such a consistency that it will partly pass through the silk or other fabric at the apertures in the plate 13. This will give a wet lacquered surface on the fabric 75 on the face side.

While the face side is still wet I next sprinkle glass globules on the front face which adhere to the fabric in the openings. These globules may be colored or not as desired.

The next step preferably employed is, after the lacquer has dried sufficiently to harden, to turn the plate over and apply clear or dyed lacquer to the back of the fabric so that it covers the fabric thickly over the openings in the plate 13. While this coating is still wet transparent globules preferably of glass are 85 preferably sprinkled on this latter side also. The globules above referred to are indicated in Fig. 5 at 17 and 18.

The article having been allowed to dry thoroughly, say for about three hours, clear lacquer is preferably applied to both the face and back of the plate, and when these layers are thoroughly dried they hold the globules 90 95 100

firmly in place, so as to allow rubbing, washing, or other rough usage.

I prefer the application of the globules to both sides as I find it gives it improved diffusion of the light. I have found that the application of the glass globules to both, or even to one side of the fabric renders it practically non-inflammable, even though the lacquer used may be of an inflammable nature.

10 In this connection it is to be understood that the term lacquer as used in my claims is intended to cover any quick drying thick substance suitable for this purpose. I have found a very suitable substance to be the thick 15 almost gummy material manufactured for use as an electric insulator, which I thin down with ordinary lacquer to the proper working consistency. It is quick drying and clear, will not soften in water and dries hard.

20 While I prefer to use silk or similar fabric in the manner above described, my invention is not limited to this material. For instance, I may use a sheet of glass either clear or colored.

25 Moreover, I may apply the adhesive to the face of the transparent sheet instead of to the back of the plate 13, and bring the two sheets together before the adhesive dries. For example, I paint or spray the front of the glass 30 with a thick coating preferably of silicate of soda, which is allowed to become semi dry or tacky. The glass is then laid over the back of the plate 13, so that it entirely covers the openings therein. The plate is then turned 35 over and the globules of glass, preferably of the same color as the sheet glass, are sprinkled on the openings in the plate 13, where they adhere to the silicate of soda on the surface of the glass plate.

40 After the silicate of soda has dried firmly, so as to attach the glass plate to the back of the plate 13, the rear of the plate is sprayed with lacquer both on the glass and on the plate 13 around it. While this lacquer is still wet, I 45 prefer to apply a piece of fabric, preferably silk, to the back of the glass and a portion of the metal around it. This renders the glass practically unbreakable and serves to aid in holding it firmly to the plate 13.

50 While I have used the term "globules" with respect to the material which is sprinkled upon the transparent sheet, it is to be understood that any small particles whatever their shape may be will be within the scope of my invention.

55 My invention may be carried out in a variety of ways which will occur to those skilled in the art and I do not limit myself to the details herein shown and described.

60 What I claim is:

1. An illuminated sign, comprising a front plate having suitable apertures, a transparent sheet secured by adhesive material to the back of the said plate, said transparent sheet being 65 fabric, and transparent globules secured by

adhesive to one side of said fabric coincident with said apertures.

2. In the process of manufacturing an illuminated sign, securing a transparent sheet by adhesive to one side of a perforated plate 70 and sprinkling transparent globules within the apertures in said plate upon the transparent sheet while the same is covered with wet adhesive.

3. In the process of manufacturing an illuminated sign, securing a transparent sheet to one side of a perforated plate, applying adhesive to both sides of said sheet, and sprinkling transparent globules on both sides of said sheet opposite the apertures in said plate 80 while the adhesive is wet.

4. In the process of manufacturing an illuminated sign, applying a strong adhesive to a sheet of transparent material, pressing the same against one side of a perforated plate, and sprinkling the adhesive within the apertures in the sheet with transparent globules before the same has time to dry.

In testimony whereof I have hereto affixed my signature on this 11th day of June 1928.

ROY E. HALLINGS.
